UNITED STATES PATENT OFFICE.

EDWARD JOSEPH DE COURCY AND ROBERT CRAWFORD, OF BELFAST,
IRELAND.

MACHINERY FOR SCUTCHING AND CLEANING FLAX.

SPECIFICATION forming part of Letters Patent No. 654,955, dated July 31, 1900.

Application filed January 9, 1900. Serial No. 844. (No model.)

To all whom it may concern:

Be it known that we, EDWARD JOSEPH DE COURCY and ROBERT CRAWFORD, subjects of the Queen of Great Britain and Ireland, and 5 residents of Belfast, in the county of Antrim, Ireland, have invented certain new and useful Machinery for Scutching and Cleaning Flax, (for which we have obtained provisional protection in the United Kingdom of Great Britain and Ireland, dated July 6, 1899, and numbered 13,945;) and we do hereby declare that the following is a full, clear, and exact description of the invention, which will enable others skilled in the art to which it appertains 15 to make and use the same.

The object of this invention is to produce machinery for scutching, beating, and cleaning flax in an expeditious and superior manner without injuring the fiber, while at the same 20 time reducing waste to a minimum.

In carrying out our invention we mount two drums in suitable framework, provided with a number of beaters parallel to each other, the longitudinal free edges of which 25 are provided with teeth or undulations formed and arranged in manner hereinafter described. These drums are so arranged in relation to each other that their respective beaters will engage slightly and freely between each other when in action. Suitable gear is provided for imparting the necessary 30 rotary motion to these drums.

The formation of the teeth or undulations of the beaters constitutes the essential feature 35 of our invention and will be understood by reference to the accompanying drawings, which form part of this specification.

Figure 1 is a front elevation of a complete machine constructed according to our invention. Fig. 2 is a vertical section on the line 2 2 in Fig. 1. Fig. 3 is a detailed view of two of the beaters, on a larger scale, showing the peculiar formation of the teeth or undulations and the relation of the beaters to each 45 other, as presently more fully described. Fig. 4 is a broken portion of Fig. 3, the scale being still larger; and Fig. 5 is a cross-section through the uppermost beater on the line 5 5 in Fig. 4.

Similar letters of reference indicate corresponding parts in each of the views.

A is the frame of the machine; B and C, the two drums mounted on shafts D and E and rotating toward each other. Motion is transmitted to these drums by the fast pulley 55 F, using the spur-wheels G and H, which are keyed to the shafts D and E. Ordinary means (not shown) are provided by which the proximity of the drums toward each other may be adjusted. J is a loose pulley. 60

It will be understood that the shafts D E are so geared together that the outer edges of the beaters K carried on one shaft are presented in the space between the beaters carried on the other shaft (see Fig. 2) and that 65 they are adjusted at such a distance apart that they do not grasp the fiber between, but treat it loosely by a motion analogous to combing. These beaters are shown in detail in Figs. 3 and 4 and we would have it expressly understood that the formation of the teeth or undulations of same constitutes the essential feature of our invention and is as follows: A section of each beater, as shown to the right of the dotted line L L, Fig. 3, is 75 provided with teeth k, consisting of regular semicircular domes and recesses above and below the pitch-line. This section, which is intended for the purpose hereinafter described, is designated for convenience the 80 "regular" section. The section on the left of the dotted line L L is provided with teeth or undulations k' of a special formation, being shaped as illustrated in Figs. 3 and 4, especially in the latter figure, which shows the 85 formation on a larger scale. These teeth or undulations k' incline in opposite directions from the extremities toward the median line P P of the section, as shown. This section we designate for convenience the "diverging" 90 section. The drums thus equipped are mounted in relation to each other in a manner whereby the teeth k k' of one drum travel around in planes between those of the corresponding teeth or undulations k k' of the 95 opposite drum. This relationship is clearly illustrated in Figs. 3 and 4. The effect of this arrangement is that in the operation of the machine as each beater comes in contact with the flax which is presented to the diverging 100 section the fibers are caused to spread laterally or diverge in a fan-like manner and are

thereby more thoroughly exposed and consequently more efficiently acted upon in the process of combing out the "shoves" in the center of the flax under treatment. The spreading action is due to the inclined faces of the teeth. One side of each tooth—that nearest the median line of the machine—is radial and has no tendency to move the fibers either toward or from that line; but the other side of those teeth the farthest from the median line is inclined and tends to move the fibers away from that line. It results that the fibers on the left are moved farther to the left and those on the right farther to the right. This action spreads the fiber in the manner which we have termed "fanwise." The domes or apices of the teeth both of the regular and diverging sections are rounded on the striking side in order to insure the easy combing or straightening of the fibers without pulling them away, while the recesses are sharp-edged to insure the efficient cleaning and beating of the fibers.

We prefer to use the machine as herein described as a "finishing-machine."

The flax may be fed to our improved machine through the hopper *t* by hand or otherwise, as found convenient.

In the operation of our improved machine the attendant takes by one end a bundle of flax, technically called a "handful," and introducing the opposite end between the drums allows it to be drawn in, or, as we prefer to term it, "carried forward," as far as possible. He then withdraws it and allows it to be again carried forward, shaking it and turning it as usual. This operation he repeats as often as occasion may require, whereupon he reverses the handful and subjects the other end to similar treatment. The flax may be passed from the diverging section to the regular section *k* or from the regular to the diverging section at pleasure, the function of the former

being both to clean and to spread and the function of the latter section being simply to clean the fibers without spreading. By skillfully alternating, at the will of the operator, so as to treat a handful first in the diverging section *k'* and afterward in the regular section *k*, the fibers will be efficiently beaten and rendered soft and silky in texture and appearance.

Having now particularly described and ascertained the nature of our said invention, we would have it understood that we do not confine ourselves to the exact formation of the teeth or undulations as herein described and illustrated, as the same may be altered in detail without departing from the principle of our invention; but

What we claim, and desire to secure by Letters Patent, is—

1. In a machine for scutching fiber the drums *B C* carrying longitudinal bars *K* arranged to slightly intermesh, provided with teeth *k'* inclined in opposite directions from a median line *P P* adapted to serve as herein specified.

2. In a machine for scutching fiber the drums *B C* carrying longitudinal bars *K* arranged to slightly intermesh, in two sections, one the divergent section having teeth *k'* inclined in opposite directions from a median line *P P* and the other regular section having upright teeth arranged adjacent adapted to serve as herein specified.

In testimony that we claim the invention above set forth we affix our signatures, in presence of two witnesses, this 6th day of December, 1899.

EDWARD JOSEPH DE COURCY.
ROBERT CRAWFORD.
